CATHODE-RAY TUBE

Constantin S. Szegho, New York, N. Y., assignor

corporation of Illinois

Application May 13, 1942, Serial No. 442,839

4 Claims. (Cl. 250—141)

This invention relates to new and useful improvements in cathode ray tubes and more particularly in tubes of the kind in which an image traced on a fluorescent screen by the electronic beam is projected through a window facing the activated surface of the screen, the so-called front projection type of tube.

In front projection tubes most of the wall of the tube envelope is coated with a conducting layer such as colloidal carbon, leaving clear only the window through which the optical image is viewed or projected. When potentials of the order of 20 kv. are employed the glass window tends to acquire an electrical charge from stray electrons which produces undesired deflections of the electron beam when it passes close to the window. The object of the present invention is to remedy this defect.

According to the present invention the window of a front projection cathode ray tube is provided with a conducting protection which is maintained at the potential of the wall coating of the tube envelope or of the fluorescent screen or any other fixed potential as required by the construction of the tube.

The potential may be applied to a conductive coating or lines of conducting material on or near the window so as to reduce any possibility of an undesired potential difference occurring at any portion of the window or portion of the window and the surrounding wall.

The lines may be of colloidal graphite or liquid silver, or the window may be coated with a thin, transparent layer of metal, for example metallic fluoride or the like preferably of such thickness that it reduces light reflections of the glass surface, or the conducting material may be incorporated in the window itself. The graphite or liquid silver may be first applied completely to cover the window and then most of it removed by ruling or similar process.

The lines thus formed on the window do not appreciably diminish the brightness of the observed image and since they are not in the focal plane of any optical system employed for the projection of the image on a viewing screen, the lines do not produce visible shadows.

Alternatively, a wire mesh may be provided between the window and the fluorescent screen in close proximity to the window and connected to the anode of the tube.

In the drawing Fig. 1 is a front view of one embodiment and Figs. 2 and 3 side elevations of two other embodiments of the invention.

The envelope is designated by the reference numeral 1 which is coated on the inside with colloidal graphite except for a window 2 made up of optically flat glass. The envelope encloses a fluorescent screen 3 opposite the window 2 which

is exposed to an electron beam produced by an electron gun 4 in neck 5 of the envelope.

In the construction shown in Fig. 1 lines 6 of conducting material are marked on the window 2; in the construction shown in Fig. 2 a wire mesh 7 is provided behind the window. The conductive protection 6 or 7 is connected with the inside conductive coating or the screen of the structure.

In Fig. 3 the elements corresponding to the other figures are designated by the same reference numerals. V_2 is the potential of a conducting coating on the wall of envelope 1 which is connected with the grid work of lines 6 on window 2. This potential is different from the potentials V_1 , V_3 and V_4 , the potentials of the first anode, the intermediate wall coating and the wall coating connected with the screen 3.

What I claim is:

1. In a cathode ray tube, a fluorescent screen, an electron gun arranged to project a beam of electrons on a surface of said screen, an evacuated envelope enclosing said screen and gun, a coating of conductive material on the inside of said envelope connected with said screen, a window of optical flat glass in said envelope opposite said screen, and conductors on said window facing said screen for keeping the electrical potential of the window at a substantially fixed level with respect to the fluorescent screen.
2. In a cathode ray tube, a fluorescent screen, an electron gun arranged to project a beam of electrons on a surface of said screen, an evacuated envelope enclosing said screen and gun, a window of optical flat glass in said envelope opposite said screen, and a coating of metallic fluoride on said window for keeping the electrical potential of the window at a fixed level with respect to the fluorescent screen.
3. In a cathode ray tube, a fluorescent screen, an electron gun arranged to project a beam of electrons on a surface of said screen, an evacuated envelope enclosing said screen and gun, a window of optical flat glass in said envelope opposite said screen, and lines of conducting material on said window for keeping the electrical potential of the window at a fixed level with respect to the fluorescent screen.
4. In a cathode ray tube, a fluorescent screen, an electron gun arranged to project a beam of electrons on a surface of said screen, an evacuated envelope enclosing said screen and gun, a window of optical flat glass in said envelope opposite said screen, and conducting material incorporated in said window connected with said screen for keeping the electrical potential of the window at a fixed level with respect to the fluorescent screen.
